GEORGE A. PIPER, OF OMAHA, NEBRASKA, ASSIGNOR OF ONE-HALF TO JOSEPH WEBER,
OF NORTH MINNEAPOLIS, MINNESOTA.

LIFTING-JACK AND PULLING DEVICE.

1,213,860.

Specification of Letters Patent. Patented Jan. 23, 1917.

Application filed June 28, 1916. Serial No. 106,343.

To all whom it may concern:

Be it known that I, GEORGE A. PIPER, a citizen of the United States, and a resident of Omaha, in the county of Douglas and State of Nebraska, have invented a new and Improved Lifting-Jack and Pulling Device, of which the following is a full, clear, and exact description.

This invention relates to lifting or pulling devices especially adapted for use in connection with automobiles as a jack for lifting the axles, and as a puller for drawing the automobile out of ruts or other places when the car is stalled.

The invention has for its general objects to provide a device of this character which has the dual function of lifting and pulling, the device being of comparatively simple and inexpensive construction, reliable and efficient in use and so designed that it can be readily converted for either use.

A more specific object of the invention is the provision of a lifting jack of that type composed of a plurality of rack bars with an intermeshing pinion, the bars being guided in a casing so that the turning of the pinion shaft will lengthen or shorten the jack, the bars being removable from the casing and the pinion being connected with winding drums, whereby cables can be attached to the drum while the shaft is mounted in the casing to enable the cables when attached to a stake and the automobile respectively, to be wound on the drum in order to pull the automobile out of the place in which it is stalled, the drums having a ratchet and pawl device to prevent them from unwinding the cables while the latter are under stress.

With such objects in view, and others which will appear as the description proceeds, the invention comprises various novel features of construction and arrangement of parts which will be set forth with particularity in the following description and claim appended hereto.

In the accompanying drawing, which illustrates one embodiment of the invention, and wherein similar characters of reference indicate corresponding parts in all the views, Figure 1 is a vertical section of the device in condition for use as a jack; Fig. 2 is a fragmentary side view thereof; Fig. 3 is a plan view while the device is used as a puller; Fig. 4 is a sectional view on the line

4—4, Fig. 1; and Fig. 5 is a diagrammatic view showing the device used as a puller.

Referring to the drawing, A designates a tubular-like casing open at both ends and divisible longitudinally on the line 1 into two similar sections which are fastened together by bolts 2 passing through lugs 3 on the sections. Slidable in the respective sections are rack bars 4 and 5 which have their teeth 6 presented toward each other, and meshing with the teeth of the opposed bars 65 is a pinion 7 on a shaft 8 journaled in the casing A. By the turning of the pinion the rack bars move in opposite directions, either lengthening or contracting the jack. The rack bars have tubular outer extremities which are internally threaded and into the bar 4 is screwed a head stem 9 on which is mounted a head or load-carrying plate 10 connected with the stem 9 by a universal joint 11. In the lower end of the rack bar 5 75 is screwed a base stem 12 which is fastened to a base plate 13. By turning the threaded stems in one direction or the other the jack can be lengthened or shortened to suit requirements. Obviously, after the jack has 80 been placed in position with the base plate 13 resting on a suitable support and the head 10 engaging the load to be lifted, such as the axle of an automobile, the pinion is turned by suitable means so that the pinion 85 will ride up on the rack bar 5, and in turn cause the rack bar 4 to move upwardly. Since the pinion is journaled in the casing A, the casing moves upwardly with respect to the rack bar 5, and consequently the rack 90 bar 4 will move twice the distance of the movement of the casing.

The outer ends of the shaft 8 have winding drums B and B' each composed of inner and outer disks 14 and 15, respectively. The inner disks have ratchet teeth 16 with which engage pawls 17 pivoted on the casing at 18 and connected together by a cross pin 19. These pawls serve to prevent the shaft 8 from turning as the jack is being used to 100 lift a load. On the outer disks or wheels 15 are spaced teeth or lugs 20, so that the forked end 21 of an operating lever 22 can be engaged with the teeth 20 to turn the pinion-carrying axle 8 by a ratchet movement, the lever after having moved its limit being disengaged from the teeth 20 of the drums and moved back so as to be engaged

with different teeth when the lever is again moved forward. The lever is detachable from the jack so that it will take up little space, and the construction is simplified.

5 When the device is to be used as a puller the rack bars and attached parts are removed from the casing by the latter being taken apart. The axle 8 and the drums are left in the casing and the cables C and C' 10 are fastened to the drums B and B' respectively, the cable C being attached to the load to be moved, such as the automobile D, Fig. 5, and the cable C', being attached to a stake which is driven in the ground. The 15 drums are now turned so as to wind up the cables, and in so doing the car is drawn toward the stake. In this manner a car when stalled can be moved to a place where the engine of the car can take care of the 20 load. The cables are normally removed from the drums so as not to be in the way when the device is used as a jack.

From the foregoing description taken in connection with the accompanying draw-

ing, the advantages of the construction and 25 method of operation will be readily understood by those skilled in the art to which the invention appertains, and while I have described the principle of operation, together with the device which I now consider to be the best embodiment thereof, I 30 desire to have it understood that the device shown is merely illustrative and that such changes may be made when desired as fall within the scope of the appended claim. 35

Having thus described my invention I claim as new and desire to secure by Letters Patent:

A device of the class described comprising a body, winding drums rotatably mounted thereon at opposite sides, teeth on the outer faces of the drums for engagement with an operating lever, means for turning the drums, and cables connected with the drums and serving to support the body when one 45 cable is fastened to an anchor and the other cable is fastened to the object to be pulled.

GEORGE A. PIPER.
